UNITED STATES PATENT OFFICE

ANNA J. GREENWICH, OF CHICAGO, ILLINOIS

WATER MARCELLING COMB

Application filed August 29, 1928. Serial No. 302,748.

This invention relates to hair dressing and has to do particularly with combs for producing a water marcel and which may also be arranged to produce a combination of water wave and marcel.

5 An object of the invention is to provide combs for water marcelling which may be readily applied and secured in proper position to produce the desired results.

10 A further object of the invention is to provide a hair dressing comb having spaced teeth with shorter teeth intermediate the first mentioned teeth.

Another object is to provide flexible arcuate combs for water marcelling having cleats thereon whereby said combs may be secured in the hair in any desired relative position.

15 A further object of the invention is to provide a water marcelling comb set having plurality of combs with cleats thereon and a plurality of elastic bands of various lengths for readily arranging said combs in any desired arrangement for producing a desired wave.

20 A further object of the invention is to provide a water marcelling comb set having plurality of combs with cleats thereon and a plurality of elastic bands of different lengths for arranging said combs in any desired position which bands are colored differently for the different lengths so that a band of desired length may be quickly selected from a pile of bands.

25 A still further object of the invention is to provide marcelling combs which are economical to manufacture, easy to apply and efficient in use.

30 The above, other and further objects of the invention will be apparent from the following description, accompanying drawings and appended claims.

35 One form of the invention is illustrated in the accompanying drawings and the views thereof are as follows:

Figure 1 is a side view of the combs arranged to produce a water marcel in hair which is parted on the side of the head.

40 Figure 2 is a top plan view of a wig showing an arrangement of combs to produce a

combined water wave and marcel with the hair parted in the middle.

Figure 3 is a top plan view of a comb showing, in full lines, same in normal position, and in dotted lines, the comb somewhat flattened as it is when applied to hair for waving purposes.

Figure 4 is an elevational view of the comb of Figure 3 looking at the concave side of the same.

Figure 5 is an enlarged sectional view on line V—V of Figure 4.

Figure 6 is a fragmental elevational view of a portion of the convex surface of the comb showing an elevational view of a cleat.

Figure 7 is a view showing one arrangement of combs in part of a wig for producing a water wave.

Figure 8 is an elevational view of a plurality of bands of various length which are used in connection with the combs of the invention.

The comb illustrated in the accompanying drawings is arcuate in plan as may be seen in Figure 3, and is made of material which permits the comb to be flexed readily from the arcuate position shown in Figure 3 to the substantially flat or applied position. The comb illustrated comprises a body 1 and a plurality of teeth 2 which are undulating in elevation. Between every pair of teeth 2 is a short tooth 3 of uniform outline. The teeth 3 project but a short distance below the body 1 of the comb.

Cleats 4 and 5 are attached to the body 1 of the comb on the convex side thereof and below the upper margin of the body. The cleats have recesses 6 and 7 whereby the elastic bands to be later described engage on either side of the cleats. The cleats are of appreciable size so as to serve as handles for applying the combs to and removing same from the hair and also serving as handles to flatten the comb for application to the hair.

Figure 1 shows a plurality of the combs applied to the hair of a person being given a water marcel. The hair is parted on the side of the head as 8. A comb A is inserted in the hair with the teeth pointing upwardly. Another comb B is applied to the hair 100.

below the comb A in a similar position. It will be noted that the combs A and B are laterally spaced and are staggered. Another comb C is arranged in the hair with 5 teeth pointing to part 8 while other combs are arranged on the other side of the head.

An elastic band 9 passes around cleats on the combs A, B and C with one part of said band passing around cleats on the combs B 10 and C and escaping a cleat on the comb A while another part of the band engages the cleats on the other ends of the combs B and C and at the left end of the comb A so as to tend to move the comb A to the right as 15 viewed in Figure 1.

The elastic band 9 serves two purposes in the arrangement just described. It tends to move the combs B, A and C bodily together thus forming waves or puffs between the 20 combs, and it also tends to move the comb A to the right thus causing a puff or wave in a different direction than that caused by the movement of the combs towards one another. The object of the combs is to produce 25 a water wave or marcel.

Figure 2 shows a wig spread open which is parted in the middle with combs D and E arranged one on each side of the middle to produce a marcel therebetween which combs 30 are connected by an elastic band 10 passing around the cleats 4 and 5 on the combs.

Beyond each of the combs D and E are other combs F, G and H in each instance being laterally spaced and also staggered. 35 An elastic band 11 passes around the cleats 4 and 5 on the comb D and engages certain cleats on certain of the other combs with a part of said band engaging but one cleat on the comb G. The arrangement of combs and 40 bands in Figure 2 produces a combination water wave and marcel in that the bands tend to draw the combs together laterally forming waves or puffs in one direction and also tends to draw certain of the staggered combs into 45 alignment thus forming waves in another direction. The combs remain in the hair for a sufficient length of time so that the waves set and become permanent for some time.

Figure 7 shows another arrangement of 50 combs to produce a water wave without the marcel.

When it is desired to form marcel, say for instance at the back of the head, then other combs would be used and connected by elastic bands of proper length.

A comb is inserted by flattening the same 60 against the head of the person whose hair is being waved so that the comb assumes a position somewhat like that shown in dotted lines in Figure 3. The comb is then pushed into the hair in this flattened state a short distance and is then given an endwise movement whereupon it is pushed further into the hair until the short teeth 3 enter the hair. Such 65 movement of the comb forms puffs or tresses

between the teeth 2 but for the short teeth 3 would form spaces between the teeth 2 in the finished wave which is undesirable. The short teeth 3 tend to spread the tresses between the adjacent teeth 2 to overcome the spaces between said tresses at present when ordinary combs are used for water waving. The curvature of the comb in normal position is greater than the curvature of the head of the person so that the comb is flattened on application. 70

The cleats 4 and 5 are placed a short distance below the upper margin of the body 1 of the comb so that the elastic bands passing over the cleats will not inadvertently be caught underneath the upper margin of the comb, and thus be hard to remove. The rubber bands used in connection with a comb set of this invention preferably are of various lengths so that even relative movement is obtained when the bands are applied to the combs arranged at different spaced intervals in the hair. I prefer to make these bands of different colors so that a hair dresser may readily pick out from a pile of bands by its 80 color the proper length she desires to use at the moment. The longest bands might be used to connect combs D and E as shown in Figure 2 while shorter bands will be used to connect the combs A, B and C in the arrangement of Figure 1. 85

The combs arranged as above described may be used for producing water waves or a combination of water waves and marcel. The water wave is produced by the spacing of the combs laterally and substantially in alignment so that when the elastic bands are applied to the combs the combs will have relative movement towards one another, so as to puff or wave the hair between such combs. The combination of water wave and marcel is secured by laterally spacing some of the combs and also staggering these endwise so that when the elastic bands are applied there will be a tendency to move the combs so connected lengthwise into alignment thus forming waves or puffs in a different direction. 90

I believe I am the first to be able to produce a marcel wave with combs as by my invention 115 I secure the combs together in such manner as to retain same in position for some time so that the marcel will set.

While I have described more or less precisely the details of construction of my invention, yet I do not wish to be understood as limiting myself thereto as I am aware that changes may be made in the arrangement and proportion of parts and that equivalents may be substituted, all without departing from 120 the spirit and scope of my invention. 125

The elastic bands, when the combs are staggered in endwise relation, engage alternate ends of the cleats so as to urge the combs into endwise alignment. It is this movement or 130

tendency of movement which creates the Marcel waves, that is, waves which run endwise from side to side of the head or in angular relation to the water waves, which water waves run lengthwise from front to back
5 of the head.

I claim as my invention:

1. A water marcel comb of flexible material having a plurality of spaced alternate long and short teeth.
- 10 2. A water marcel comb of flexible material having handle-like cleats near the upper margin thereof, said cleats being spaced below said upper margin.
- 15 3. A water marcel comb set including a plurality of arcuate flexible combs having a plurality of spaced alternate long and short teeth, handle-like cleats on the convex sides of said combs, and elastic bands of different lengths cooperable with said cleats for retaining said combs in the hair.
- 20 4. A water marcel comb set including a plurality of combs arranged in laterally spaced and endwise staggered relation, every comb having two spaced cleats thereon, an elastic band engaging said cleats with one run of the same hooking alternate ends of the cleats at similar ends of the combs and the other run hooking alternate ends of the cleats at the other ends of the combs in such manner as to draw together and endwise align said combs.
- 25 5. A water marcel comb of flexible material which is curved in plan, said comb having a plurality of spaced alternate long and short teeth, and handle-like cleats on the comb, every cleat having double hooks on the same.
- 30 6. A water marcel comb comprising an elongated back member, longitudinally spaced integral teeth extending from said member, said teeth being undulated in outline in the direction of the length of the comb, and integral straight teeth extending from said back member arranged intermediate said first-named teeth and being substantially shorter than said first-named teeth.
- 35 45

In testimony whereof I have hereunto subscribed my name at Chicago, Cook County, Illinois.
